UNITED STATES PATENT OFFICE

2,650,413

APPARATUS FOR UNCURLING FABRIC EDGES

John H. Pope, Hopewell, and Nelson W. Carter,
Petersburg, Va., assignors to Celanese Corpora-
tion of America, a corporation of Delaware

Application June 22, 1948, Serial No. 34,474

3 Claims. (Cl. 26—1)

1

This invention relates to the processing of fabrics and relates more particularly to a novel apparatus for uncurling the curled edges of fabrics.

As is well known, the edges of flat fabrics, especially flat knitted fabrics, show a strong tendency to curl towards one surface or the other of the fabric. In fabrics knitted on a one or two-bar tricot warp-knitting machine the edges curl toward the back or bottom surface of the fabric, but in other fabrics the edges may curl toward either the face or the back of the fabric. It is necessary that these edges be uncurled before the edges of two pieces of fabric or the two edges of a folded single fabric are joined. Usually the edges of two fabrics are joined for the purpose of having selected sides of the fabric face each other to produce a certain effect in the final product, whereas the two edges of a single fabric are joined to form a tube preparatory to dyeing or other treatment.

It has previously been proposed to uncurl the two edges of a single fabric, preparatory to joining them to form a tube, by superimposing the edges with the curled portions facing away from each other and passing the superimposed edges between two opposed continuous belts running at right angles to the direction of travel of the fabric and in frictional contact with the curled edges. When the edges of the fabric curl toward the side of the fabric which it is desired to have on the inside of the tube, it is necessary, when employing the foregoing expedient, to turn the joined fabric tube inside out, before dyeing or other treatment, which is obviously a time consuming operation. Furthermore, when the edges of two fabrics are to be joined and the curl of the edges is toward the sides of the fabrics which are to face each other during joining, it has been impossible to employ this expedient. Moreover, the prior apparatus employed was also disadvantageous in that it required two uncurling belts, together with means to drive each of them as well as means to adjust and hold them a suitable distance apart. This resulted in a relatively complex structure which if not kept properly adjusted would not satisfactorily uncurl the edges of the fabric or would permit one of the two uncurling belts to pull the edge of the fabric it was uncurling out of alignment with the other edge of the fabric.

It is an important object of this invention to provide an apparatus for simultaneously and continuously uncurling two curled fabric edges which face each other which will be free from

2

the foregoing disadvantages and which will be especially simple in construction and efficient in use.

It is another important object of this invention to provide an improved method of uncurling two curled fabric edges which face each other.

10 A further important object of this invention is to provide an improved apparatus for and method of forming a fabric tube from a flat fabric.

15 Other objects of this invention, together with certain details of construction and combinations of parts, will appear from the following detailed description and claims.

20 The foregoing objects may be achieved by facing two curled fabric edges toward each other and passing an uncurling member between and in frictional contact with the curled edges in a direction having a component transverse to the edges. It has also been found that a flat fabric may be converted to tubular form by doubling the fabric with its curled edges facing each other, passing an uncurling member between and in frictional contact with the edges to uncurl them, trimming the edges, if desired, and joining them together by sewing or in any other manner.

25 A preferred embodiment of the invention is illustrated in the annexed drawings, in which Fig. 1 is a perspective view of the uncurling apparatus showing a fabric being treated,

30 Fig. 2 is a side elevation of the uncurling apparatus with the edge trimmer and sewing machine omitted for clarity and,

35 Fig. 3 is a plan view of the uncurling apparatus as shown in Fig. 2.

40 Referring to the drawings the reference numeral 1 represents the fabric being operated upon by the uncurling apparatus of this invention wherein the various elements are mounted on a base plate 2 which may be a separate plate as shown, or may be an extension of sewing machine table top 3. Alternatively, the base plate 45 may be eliminated completely and the various elements supported independently.

45 Secured to the base plate 2 is an angle-iron bracket 4 to which is adjustably fastened the lower uncurling plate assembly generally indicated by reference numeral 5. This lower uncurling plate assembly includes an arm 6 having an elongated slot 7 and is fastened to the bracket 4 by bolts 8. The arm 6 has fixed thereto or integral therewith a lower uncurling plate 9 having a free end 10 which is bent away from

the plane of the plate forming a rounded edge over which the fabric may be drawn without being damaged.

Also fastened to the base plate 2 is a second bracket 11 carrying a T-shaped supporting member 12 having the ends 13 of its arms 14 bent at right angles to the plane of the T. Holes 15 are provided in the ends 13 of each of the arms 14 and a shaft 16 is passed through these holes. Pivotaly mounted on the shaft 16 is the upper 10 uncurling plate assembly generally indicated by reference numeral 17, which includes the arm 18 and an upper uncurling plate 19. The uncurling plate 19 is spring-pressed toward the uncurling plate 9 by a spring 20 which is fastened to the arm 18 by bolt 21 and to the base plate 2 by means of eye bolt 22. An adjustable stop 23 is provided to limit the downward travel of the arm 18 carrying the uncurling plate 19. The stop 23 is fastened to the T-shaped supporting 20 member 12 by means of nut and bolt 24 and may be adjusted by rotation about the axis of the bolt 24 and by shifting its position along slot 25.

The edges of the uncurling plates 9 and 19 may be chamfered or rounded to reduce the friction between them and the fabric being treated, which chamfering or rounding may be restricted to the forward edges of the uncurling plates since these are the edges first approached by the fabric.

The bracket 11 is also adapted to support arm 26 having a slot 27 in its free end and an idler pulley 28 is adjustably mounted in said slot 27 by means of nut and bolt 29. A shaft 30 mounted on bracket 31 carries two pulleys 32 and 33 which may be integral or may be fastened together by means of a bearing member 33' to rotate as a unit. Belt 34 driven by any suitable means (not shown) is trained about pulley 33 and drives pulley 32 about which and pulley 28, 40 the uncurling belt 35 is trained, the belt 35 moving in the direction indicated by the arrows.

The uncurling belt 35 may be a round belt formed of rubber or other suitable material having a frictional surface. The uncurling belt 35 may not only be round, but may have a square, rectangular or other cross-section presenting similar opposing surfaces to the fabric in which case the grooves of the pulleys 28 and 32 must match the shape of the belt to prevent its twisting.

Any suitable cutting device, illustrated diagrammatically at 36, may be provided to trim the edges of the fabric if desired. The edges of the fabric may be joined in any manner such as by sewing with a conventional sewing machine 37 to produce an overedge stitch 38, in which case the fabric edges will abut each other when the seam is laid flat. Alternatively a chain stitch may be used and the fabric edges will overlap, 50 when the seam is laid flat.

When the uncurler is employed in producing a tube of fabric from a flat fabric the fabric is doubled with its curled edges facing each other in any suitable doubling machine. The lower edge of the fabric is fed under the arm 26 under a suitable guide and between the uncurling plate 9 and the uncurling belt 35. The upper edge of the fabric is fed over the arm 26 over a suitable guide and between the uncurling plate 19 and the uncurling belt 35. The clearance between the uncurling plates 9 and 19 and the uncurling belt 35 is such that the belt will frictionally engage the curled edges only of the fabric. The belt 35 operates at a linear speed greater than 60

the linear speed of the fabric as it travels through the uncurler, and uncurls the edges of the fabric as they pass between the belt and the uncurling plates. The edges of the fabric may be trimmed and are then fastened together. After the fabric has been dyed or otherwise treated it may be rolled in the form of a tube for storage or the joined edges of the fabric may be unfastened by cutting, trimming or in any other manner and the fabric restored to the flat state.

One particular physical arrangement of elements has been shown, but many others are possible without departing from the spirit of the invention. For example, the cutter 36 and sewing machine 37 may be on a different level from the uncurling apparatus and suitable guides or rollers may be provided to lead the fabric from one level to another. Instead of operating the uncurling apparatus with the uncurling plates 9 and 19 and the uncurling belt 35 in a horizontal plane as shown, the entire apparatus may be operated with the uncurling plates and the uncurling belt at any angle up to and including the vertical. Furthermore, it may be desirable to feed the fabric into the uncurler and take it away from the uncurler by means of guides or rollers, but the number and arrangement of guides or rollers will depend entirely on the plant layout and the fabric treatment being applied.

30 In the drawings the uncurling belt 35 travels at right angles to the direction of travel of the fabric. It is unnecessary that the belt and the fabric edge be at right angles so long as the travel of the belt has a component at right angles to the direction of travel of the fabric.

35 The uncurling machine may be constructed of any suitable materials. Although bolts and nuts have been shown as the fastening means between the members they may be replaced by any other suitable fastening means, such as welding, at those points where adjustability is not desired.

40 It is to be understood that the foregoing detailed description is given merely by way of illustration and that many variations may be made therein without departing from the spirit of our invention.

45 Having described our invention, what we desire to secure by Letters Patent is:

1. Apparatus for uncurling fabric edges comprising an uncurling plate having a flat surface, another uncurling plate having a flat surface spaced from and generally parallel to the flat surface of said first uncurling plate, means for varying the distance between said uncurling plates, said uncurling plates being adapted to guide the curled edges between them, an endless belt passing between and spaced from said flat surfaces to frictionally engage and uncurl the fabric edges, and means for limiting the motion of the uncurling plates toward each other so that the endless belt engages the curled edges only of the fabric.

2. Apparatus for uncurling the edges of a fabric comprising an uncurling plate having a flat surface, another uncurling plate having a flat surface spaced from and generally parallel to the flat surface of said first uncurling plate, said uncurling plates being adapted to guide the curled edges between them, one end of said first uncurling plate being bent at an angle away from said other uncurling plate to present a smooth bearing surface to a fabric, said uncurling plates being mounted for relative motion towards each other, a spring for urging said uncurling plates towards each other, an adjustable stop limiting the motion of the uncurling plates towards each

other, and a driven endless, beltlike uncurling member of circular cross-section passing between said uncurling plates to frictionally engage and uncurl the fabric edges.

3. Apparatus for uncurling the edges of a fabric comprising an upper uncurling plate having a flat surface, a lower uncurling plate having a flat surface spaced from and generally parallel to the flat surface of said upper uncurling plate, said uncurling plates being adapted to guide the curled edges between them, one end of said lower uncurling plate being bent at an angle away from said other uncurling plate to present a smooth bearing surface to a fabric, an adjustable mounting carrying said lower uncurling plate for permitting vertical movement thereof, a pivotal mounting for the upper uncurling plate, a spring

for urging the upper uncurling plate toward the lower uncurling plate, adjustable stop means limiting the motion of the upper uncurling plate, and a driven endless, beltlike uncurling member of circular cross-section passing between said uncurling plates to frictionally engage and uncurl the fabric edges.
